CLAIM

The ornamental design for a scooter, as shown and described.

DESCRIPTION

FIG. 1 is a perspective view of a scooter showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view thereof showing the scooter in the usage status;

FIG. 10 is another perspective view thereof showing the scooter in the usage status;

FIG. 11 is a front view thereof showing the scooter in the usage status;

FIG. 12 is a rear view thereof showing the scooter in the usage status;

FIG. 13 is a left side view thereof showing the scooter in the usage status;

FIG. 14 is a right side view thereof showing the scooter in the usage status;

FIG. 15 is a top view thereof showing the scooter in the usage status; and,

FIG. 16 is a bottom view thereof showing the scooter in the usage status.

The dashed broken lines illustrate portions of the scooter that form no part of the claimed design.
